UNITED STATES PATENT OFFICE.

JOHN E. HAGER AND ROBERT H. PORTEOUS, OF NEW YORK, N. Y.

PENCIL-SHARPENER.

1,026,671.

Specification of Letters Patent. Patented May 21, 1912.

Application filed December 11, 1911. Serial No. 664,980.

To all whom it may concern:

Be it known that we, JOHN E. HAGER and ROBERT H. PORTEOUS, citizens of the United States, residing at New York, in the county 5 of New York and State of New York, have invented certain new and useful Improvements in Pencil-Sharpener, of which the following is a specification.

Our invention relates to pencil sharpeners 10 and has for its object to provide a simple device which readily serves the double purpose of a pencil point protector and a point sharpener.

With these and other objects in view, 15 which will appear as the nature of the invention is better understood, the same consists in certain novel features of construction, as hereinafter fully described and claimed.

20 In the accompanying drawings: Figure 1 is an enlarged vertical sectional view. Fig. 2 is a horizontal sectional view on line A—B Fig. 1. Fig. 3 is a side view. Fig. 4 illustrates different shapes of pencil points 25 which may be obtained by correspondingly shaping the sharpening member. Fig. 5 is a detail view of one of the sections.

In the drawings wherein like reference numerals indicate corresponding parts 30 throughout the several figures, 5 represents a tubular sleeve or casing preferably of sheet metal having a somewhat restricted upper portion 6 and an enlarged lower portion 7. The lower end of the portion 7 has the usual 35 indentations 18 for holding a rubber eraser if so desired.

Confined within the portion 7 is the 40 sharpening device 8 consisting of a plurality of tapering sections 9 of carborundum or other suitable material, which sections as best illustrated in Fig. 5 are of gradually increasing size from their upper ends to the lower ends thereof. The inner faces of 45 these sections are provided with graduated file like projections 10 which decrease in size as they approach the lower ends of their respective sections. It will thus be seen that a conical opening 11 is formed when the several sections are assembled as 50 just described. The pencil point is inserted in this opening 11, and by a relative oscillatory or rotary movement of the sleeve 5 and pencil 12 the file surfaces 10 quickly remove the wood from the pencil.

55 To prevent the waste material from clog-

ging up and interfering with the operation of the sharpener, the marginal inner adjacent faces of each section 9 are formed perfectly smooth to produce inclined pockets or recesses 13 between the toothed portion of 60 the sections. These pockets can be emptied after the pencil has been sharpened and removed by inverting the sleeve 6 and subjecting the latter to a sharp blow. The finer waste materials, principally the scrapings 65 from the lead tip escape into a pocket 14 formed in the sections 9 adjacent their bases. It will be seen from an inspection of Fig. 1, that the pocket 14 is in reality composed of a plurality of grooves 15 in the several sections 70 9 which when the sections are assembled register. A transverse channel 16 leads from the pocket 14 to oppositely disposed openings 17 in the sleeve 6.

While we have shown and described the 75 sharpener 8 as made up of a plurality of sections it is obvious that it would not involve invention to make the same of a single piece of wood or other material.

By slightly altering the curvature of the 80 inner faces of the sections 9 it will be seen that the taper imparted to the pencil being sharpened can be of any desired shape or slope.

It has been found in practice that by 85 graduating the teeth 10 from fairly coarse at top to finer at the bottom the danger of breaking the lead is greatly lessened without impairing the effectiveness or rapidity of the sharpening operation. 90

Having thus described our invention, what we claim is:

A pencil sharpener comprising a tubular sleeve adapted to fit over the end of a pencil, a plurality of tapering sections within said 95 sleeve, said tapering sections being grooved to form a pocket, the inner walls of said sections being spaced to form a conical opening, file like projections on the inner faces of said sections, and said sections having 100 smooth portions adjacent their abutting side edges to form inclined pockets.

In testimony whereof we affix our signatures in presence of two witnesses.

JOHN E. HAGER.
ROBERT H. PORTEOUS.
